UNITED STATES PATENT OFFICE.

CYRUS EBERLY, OF COLUMBUS, OHIO.

WINDOW CURTAIN CORNICE.

SPECIFICATION forming part of Letters Patent No. 279,232, dated June 12, 1883.

Application filed December 27, 1882. (No model.)

To all whom it may concern:

Be it known that I, CYRUS EBERLY, a citizen of the United States, residing at Columbus, in the county of Franklin and State of Ohio, have invented certain new and useful Improvements in Window Curtain Cornices; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 The present invention relates to the class of window curtain cornices composed of a stationary center piece and sliding sides or wings moving in grooves or ways of said center piece, and operated by an endless cord secured to the inner ends of the side pieces and 20 passing around pulleys at the ends of the center piece.

The object of the invention is to dispense 25 with the pulleys heretofore employed for the guidance of the endless cord, thereby making a cornice of the class above mentioned more simple in construction and less expensive than heretofore.

The invention consists in the provision of 30 bridge pieces or plates, made of metal, wood, glass, or other suitable material, which are secured to the back side of the stationary center piece, and have formed therein or thereon fixed curved guide grooves or ways for the 35 reception and guidance of the endless cord connected with the adjustable wings. These bridge-plates are located at the ends of the center piece and extend across the groove or way in which the adjustable wings slide, and 40 serve to hold the latter in place.

In the drawings, Figure 1 is a rear view of 45 an extensible cornice, showing metallic bridge-plates provided with cord ways or grooves, which are formed by turning up a series of prongs on the side of each bridge-piece. Fig. 2 is a perspective view of one of said metallic bridge-plates. Fig. 3 is a rear view of a cornice having wooden bridge-pieces with curved or semicircular cord-grooves cut in their faces.

Figs. 4 and 5 are detail views of a grooved 50 bridge-piece.

The letter A designates a stationary center piece, which has a groove or way on its rear face for the reception and retention of the extensible side pieces, B. These side pieces are 55 connected together by the endless cord C, so as to allow them to be extended evenly and simultaneously and cause the center piece to always remain exactly in the middle of the window or other casing to which the cornice 60 is applied. The endless cord is secured to the extensible arms at their inner or meeting ends, as is shown at a, and it passes around curved or semicircular guide grooves or ways D, formed on or in bridge-plates E, which are secured to the center piece, A.

As shown in Figs. 1 and 2, the guideway for the endless cord is formed on a sheet-metal plate by cutting out a series of prongs or spurs, F, at the edge of said plate, and as these 70 prongs are cut on a semicircular or curved line, they will, when turned up or bent over, form a groove or way in which the cord is retained and can freely move. The bridge-plates E are located at the ends of the center 75 piece, and, in addition to being provided with the cord-grooves, as stated, they hold the sliding sections or arms in place.

In the construction shown in Figs. 3 to 5, inclusive, the bridge-plate is made with a 80 curved or semicircular groove, G, which is sunk into the face of the plate, and has the edges or walls thereof cut obliquely, or on a bevel, as is clearly shown in Fig. 4. In other words, the groove is undercut, or is of a dove- 85 tail shape, so that the cord will remain securely seated therein.

The bridge-plate shown in Figs. 3, 4, and 5 is generally made of wood; but it may be of metal, glass, or any other suitable material. 90

What I claim as my invention, and desire to secure by Letters Patent, is—

1. In an extensible window curtain or other cornice, the combination of bridge or back plates, having fixed or stationary semicircular or curved grooves or ways formed therein or thereon, with the stationary center piece, extensible side arms, and endless operating-cord

secured to said side arms and moving in the ways or grooves of the bridge-plates, substantially as herein set forth.

2. A bridge-plate for an extensible window curtain or other cornice, having formed therein a semicircular or curved groove or way for a cord to slide in, substantially as herein set forth.

In testimony whereof I affix my signature in presence of two witnesses.

CYRUS EBERLY.
